UNITED STATES PATENT OFFICE.

FRANCIS H. RICHARDS, OF HARTFORD, ASSIGNOR TO THE AMERICAN
BUTTON-FASTENER COMPANY, OF NEW BRITAIN, CONNECTICUT.

BUTTON-SETTING INSTRUMENT.

SPECIFICATION forming part of Letters Patent No. 439,604, dated October 28, 1890.

Application filed March 3, 1890. Serial No. 342,478. (No model.)

To all whom it may concern:

Be it known that I, FRANCIS H. RICHARDS, a citizen of the United States, residing at Hartford, in the county of Hartford and State of Connecticut, have invented certain new and useful Improvements in Button-Setting Instruments, of which the following is a specification.

This invention is in the nature of an improvement on the button-setting instrument described in United States Patent No. 338,554, granted to me March 23, 1886.

In the drawings accompanying and forming a part of this specification, Figure 1 is a side elevation of a button-setting instrument embodying my present improvements and showing the jaws or members open, with a fastener in place ready for setting. Fig. 2 is a similar and corresponding view, partially in section, showing the jaws closed, as at the close of the setting operation. Fig. 3 is a plan view of the under side of the lower jaw, showing certain details of construction. Fig. 4 is a front view of the lower member and the parts thereon. Fig. 5 is a detail in three views of the front end of the lower jaw. Fig. 6 similarly shows the bifurcated presser-slide in three views. Fig. 7 represents a face view of bifurcated presser-slide, showing the springs in position therein.

Similar characters designate like parts in all the figures.

The two handles A B of my improved instrument are or may be of the usual description and pivoted together at X in any usual manner, substantially as shown. A spring 54 may be employed to hold the handles normally in their open position. (Shown in Fig. 1.)

The upper jaw D, which is the button-holding member, has formed therein the usual setting-die E. It may also be provided with a button-holding spring, after the manner described in my United States Patent No. 311,033, dated January 20, 1885. In the absence of such spring or equivalent means, the button 30 is held by the operator with its shank under said setting-die in the usual manner, substantially as shown in Fig. 2.

The lower jaw C, which is the fastener-

driving member, is shaped to form a passage 60, Fig. 5, for receiving the presser-slide F. This slide has between the parts thereof a space 42, through which the wall 40 extends to carry the driver, and in this space, when the slide is down, as in Fig. 2, the spring H also passes, as shown in this figure. The plate formed on the middle wall 40 in front of said channels constitutes the driver N, on the upper edge of which the fastener-head 2 rests, as shown in Figs. 1, 2, and 4. The driver-plate N has a guard 62 for holding the head 2 in place contiguous to said slide during the operation of setting the fastener.

As a means of operating the slide F, springs 65 10 are provided, and are conveniently carried in suitable chambers 11 in said slide. The spring 10 rests on the projecting spring-sustaining abutments 12 of the wall 13 between the slide-channels 60. The spring 10, 70 itself contained within said pocket or recess 11, formed within the slide F, bears against and forces up the same. The slide F is formed, preferably, in two parts joined at 14 and united by a pin 15, whereby the two parts 75 operate as one. Said parts are oppositely disposed, and have a guide or rib 16 that slides in the grooves 17 of channels 60, whereby said slide parts are securely held and guided. A stop 18 serves to limit the upward motion of 80 the slide.

A fastener-holding spring or fastener-presser H is attached at 19 to the member C, and is adapted to hold the fastener 5, Figs. 1, 2, and 4, in place against said slide above 85 the driver. For this purpose the spring has a point 21, having a backward tension and curved to permit the fastener-head to be slipped thereunder. Said spring H normally stands as in Fig. 1, but is adapted to be carried down, as in Fig. 2, where the upper member D forces the material down over the prong 5, as there shown.

The mode of operating my improved instrument is substantially the same as that of operating the instrument described in my afore-said patent, No. 338,554, and will be obvious to those skilled in this art from the drawings and preceding description. The jaws C D being open, a fastener is pushed under the 100

spring-point 21 into position ready for setting, as in Figs. 1 and 4. The button 30 being now put or held in place, and the fabric or shoe-upper M being properly placed over the slide 5 F, the two jaws are now forcibly brought together. This pushes down slide F and drives the fastener-prong up through the fabric and button-shank against the setting-die, thereby clinching the prong and completing the setting operation.

Having thus described my invention, I claim—

1. In a button-setting instrument, the combination, with the member C, having oppositely-disposed slide-receiving spaces, substantially as described, and having spring-sustaining abutments 12 located in said spaces, of the slide F, and springs carried within said slide and resting on said abutments, substantially as described.

2. In a button-setting instrument, the combination, with the member C, formed with the slide-receiving spaces 60, of the slide F, consisting of two oppositely-disposed parts, fitting 25 in said spaces and meeting above said member, and a spring located in each part of said slide, all substantially as described.

3. In a button-setting instrument, the combination of the lower member having the 30 driver N and carrying the presser-slide, of the

fastener-holding spring H, having the presser-point 21 and under tension, all substantially as described.

4. In a button-setting instrument, the combination of the member C, having the middle wall 40 and driver N, of the bifurcated presser-slide and the fastener-holding spring H, below said wall 40 and extending between the parts of said slide when the slide is down, all substantially as described. 35

5. In a button-setting instrument, the combination, substantially as described, of the member having the driver, a slide contiguous to the driver, a guard on the driver holding the fastener-head contiguous to the slide, and 45 the fastener-presser holding the fastener toward said slide.

6. In a button-setting instrument, the combination, substantially as described, of the member having the driver and formed to receive the bifurcated slide, of the spring-sustaining abutments on said member, the recessed oppositely-disposed slide members, a spring located in each part of said bifurcated slide, and a removable stop limiting the 50 movement thereof. 55

FRANCIS H. RICHARDS.
